UNITED STATES PATENT OFFICE

ARTHUR E. NASH, OF PHILADELPHIA, AND JAMES S. ALCORN, OF CYNWYD, PENNSYLVANIA, ASSIGNORS TO ALCORN COMBUSTION COMPANY, OF PHILADELPHIA, PENNSYLVANIA, A CORPORATION OF DELAWARE

RADIATION COMBUSTION CHAMBER

Application filed November 29, 1926. Serial No. 151,307.

Our invention relates to radiation combustion chambers, as passages wherein the combustion progresses as the fuel, air and gases progress therethrough.

In accordance with our invention, the wall structure forming a chamber or passage from which heat is transferred by radiation to a heat absorption structure, either wholly or in part, is formed of a metal or alloy having high heat conductivity and capable of withstanding high temperatures.

Further in accordance with our invention, the aforesaid metal or alloy should be chemically inert with respect to the gases developed by the burning fuel and should be of a character largely resisting oxidation at high temperature.

Further in accordance with our invention, a combustion chamber comprising wall structure constructed of a metal or alloy, as aforesaid, is utilized for radiating heat to suitable structure capable of absorbing the heat at a rate preventing excessive rise in temperature in said wall structure.

Our invention resides in a radiation combustion chamber of the character herein-after described and claimed.

For an illustration of some of the many forms our invention may take, reference is to be had to the accompanying drawing in which:

Fig. 1 is a vertical sectional view of heat transfer apparatus embodying a radiation combustion chamber constructed in accordance with our invention.

Figs. 2 and 3 are end and vertical sectional views, respectively, of a tubular combustion chamber constructed in accordance with our invention.

Figs. 4 and 5 are end and vertical sectional views, respectively, of another form of a combustion chamber.

Figs. 6 and 7 are end and vertical sectional views, respectively, of another form of a combustion chamber.

Fig. 8 is a transverse vertical sectional view of still another form of a combustion chamber.

Fig. 9 is a vertical sectional view of still another form of a combustion chamber. 50

Fig. 10 is a vertical sectional view of the structure shown in Fig. 9.

Fig. 11 is a vertical sectional view of still another form of a combustion chamber.

As exemplified in the U. S. patent to Cannon, 1,371,774, it is known to the art that carborundum may be utilized for forming a combustion chamber for transferring or radiating heat to heat-absorption structure. 55

In accordance with our invention, in lieu of carborundum as the material from which the combustion chamber is formed, there is utilized a metal or alloy capable of withstanding high temperatures, of high heat conductivity, and to the proper degree resistant to oxidation at high temperature and to the chemical effect of the products of combustion. As examples of metals or alloys that may be thus utilized, there may be cited iron, steel, copper, nichrome and the chrome iron 70 and nickel alloys. The utilization of a metal or alloy has many advantages over silicon carbide, fire brick or similar refractory material. For example, various shapes and cross sections may be readily manufactured, the heat 75 conductivity is substantially greater, and the wall structure may be thinner with resultant decreased resistance to the passage and transfer of a greater amount of radiant heat. Further, metal or an alloy has much greater structural strength than a refractory material, as aforesaid, and, therefore, there is less danger of failure through cracking. The simplicity of installation and possibility of utilizing particular alloys which would resist certain 80 specific conditions which are sometimes encountered and where refractory materials cannot be used is also an advantage.

The combustion chamber, dependent upon the circumstances, may be of any suitable con- 90

figuration. Ordinarily, however, it simulates a tube or passage having a length many times as large as its greatest transverse dimension. For example, in Figs. 2 and 3 there is illustrated the round or circular metallic structure A, preferably tube-like or elongated and having a length substantially greater than its diameter.

10 Where it is desirable to provide a large radiating surface, the simple tube-like structure A of Fig. 2 may be replaced by the structure B of Figs. 4 and 5 wherein the radiating surface is undulating or corrugated.

15 In the form of our invention illustrated in Figs. 6 and 7, there is illustrated a combustion chamber comprising the metallic structure C of semi-circular or equivalent cross section having a smooth surface, or one that is irregular or corrugated, preferably the latter. The structure C may be seated on a base or support D of metallic or non-metallic material. Preferably, however, the material from which base D is formed is refractory, as

20 25 In Fig. 8, there is illustrated a metallic radiating structure E shaped substantially as an inverted U and supported upon the preferably refractory base F. Here again the structure E may be plane or corrugated as found most desirable.

30 35 In Figs. 9 and 10, there is illustrated a plurality of spaced supports or piers G constructed of material, as brick, suitably resistive to high temperature. Disposed upon the supports G are the metallic members or plates H whose ends preferably overlap as illustrated in Fig. 9. As with the forms of our invention heretofore illustrated, the members H may be corrugated or plain as desired. In the form of our invention illustrated in Figs. 9 and 10, the space between adjacent piers G and beneath a member H constitutes a combustion chamber wherein combustion of fuel occurs with evolution of heat which is radiated from the member H.

40 45 In Fig. 11, there is illustrated a form of our invention wherein the combustion chamber comprises the wall structure I of any suitable shape and formed either wholly or partially of a metal or alloy. Disposed within the structure I is the refractory lining J, preferably constituting a chamber formed by sections or slabs of silicon carbide or the like. The burner B1 discharges fuel of any suitable character interiorly of the structures I and J, the latter being preferably disposed in the region wherein occurs the most intense combustion. Under some circumstances, it may be that the highest rate of heat evolution does not occur at the extreme left of the structure shown in Fig. 11 in which case the refractory structure J may be moved toward the right, leaving metallic wall structure alone in the immediate vicinity of the burner B1. It may also be

desirable to modify the structure illustrated in Fig. 11 by eliminating that part of the metallic wall structure I which overlies the structure J in which case the most intense combustion occurs in a simple refractory combustion chamber, the gases after becoming somewhat cooler passing to the metallic combustion chamber I, both chambers, however, functioning to radiate heat to the heat absorption structure.

50 55 Within any of the combustion chambers constructed in accordance with our invention, there may be effected combustion of any suitable material, solid or fluid. For example, gas or oil may be introduced at one end of the particular combustion chamber in service, the combustion progressing toward the other end thereof as the fuel, air and gases progress therethrough. As a result, the metallic wall structure becomes a source of radiant heat, usually incandescent in character, but, due to the fact that its heat conductivity is high, the temperature thereof does not become of sufficient magnitude to cause damage. Thus, for example, while the temperature interiorly of the combustion chamber may range upwardly to 3200 degrees F. or more, due to the rapid transfer of heat through and from the metallic wall structure, the temperature exteriorly of the combustion chamber fails to attain a magnitude such as will cause melting or softening of the said wall structure. This mode of operation, of course, is based on the assumption that exteriorly of the combustion chamber there is provided heat absorption structure capable of absorbing the heat at substantially the same rate that it is radiated from the metallic wall structure.

60 65 In general, it may be stated that the temperature of the radiant wall structure of the combustion chamber is roughly proportional to the rate at which heat is absorbed by the heat-absorption structure. Accordingly, the character of the metal to be utilized in a particular installation is, in a way, dependent upon the rapidity of absorption of heat by the heat-absorption structure. For, if heat is absorbed at an extremely rapid rate, the metal entering into the combustion chamber wall structure may have a relatively low melting point. But under different conditions, as when heat is absorbed at a relatively slow rate, the metallic wall structure must be of such character that it will not melt at a relatively high temperature.

70 75 The thickness of the combustion chamber wall structure may be such as is suitable and desirable. Ordinarily, the thickness is substantially less than that of a combustion chamber whose wall structure is formed from silicon carbide or the like but should be such as will produce a rigid structure and one which will not unduly warp or bend un- 80 85 90 95 100 105 110 115 120 125 130

der the influence of the high temperature developed in the combustion chamber.

Merely by way of example, and without limitation of our invention, in Fig. 1 there is illustrated heat transfer apparatus of the general character disclosed in our U. S. Patent No. 1,591,431, modified, however, by the provision of a combustion chamber comprising metallic wall structure in lieu of the therein-disclosed silicon carbide combustion chamber. In Fig. 1, 1 is a heating chamber whose walls may be of brickwork or the like and whose bottom or floor 2 comprises any suitable filling, preferably overlaid by a layer 15 or course 3 of fire brick or equivalent.

Disposed within the heating chamber 1 are the tubes 4, of iron, steel or other suitable material, extending in any suitable direction, as, for example, horizontally, as indicated, or 20 inclined when suitable or desirable. All the tubes 4 may be connected in any suitable arrangement, as, for example, in tandem or in series with each other by couplings or headers, not shown, preferably disposed externally 25 to the chamber 1.

When desirable, there may be provided tube-supporting means, such, for example, as the pier 5 upon which is disposed the tube-supporting member 6 of fire brick or other 30 suitable refractory material.

Disposed within the chamber 1 is a radiation combustion chamber C comprising a metallic wall structure, which, for example, may be of the character illustrated in Figs. 6 and 35 7. It shall be understood, however, that in lieu of the combustion chamber disclosed in Figs. 6 and 7 there may be thus utilized a combustion chamber of the character elsewhere disclosed herein, or any other suitable 40 type of combustion chamber whose wall structure either wholly or in part is metallic in character or a combination of refractory and metallic wall structures as illustrated in Fig. 11.

45 Gas or oil supplied to the burner B1 is burned within the combustion chamber, the combustion progressing as the fuel, air and gases progress through the chamber and part of the heat of combustion being utilized to 50 raise the wall structure C to suitably high temperature to effect suitable rate of radiation of heat to the tubes 4 within the chamber 1 from which the hot gases of combustion are more or less completely excluded.

55 The hot gases or products of combustion pass from the combustion chamber into the bottom chamber 8 of the stack formed by the walls 9, then upwardly around and between the tubes 10 disposed in the stack, and thence 60 to any suitable destination. The tubes 10 may be connected in any suitable arrangement, as by couplings or headers, not shown, but preferably located externally to the chamber 8. The tubes 4 and 10 may be connected in series 65 with each other by a connection 11.

A fluid, as petroleum, or a component or product thereof, may be heated by the structure disclosed in Fig. 1 for effecting a desired result. For example, the oil may be first passed through the tubes 10 preheating it to 70 a desired temperature, and thereafter passed through the tubes 4, where it may be subjected to the same or different temperature, generally a high temperature. For example, oil may be subjected to conditions effecting dissociation or cracking in the tubes 10 or tubes 4, or in both, under any suitable pressure, as super-atmospheric pressure. Thus, to the heat-absorption structure comprising the tubes 4 substantially exclusively radiant heat is applied, 75 which is radiated thereto through substantial intervening space, from the metallic wall structure of the combustion chamber. To the tubes 10 heat is applied by convection, since the hot gases emerging from the combustion 80 chamber pass into contact therewith. The same tubes 10 are likewise heated by radiation resulting from the highly heated walls 9 of the chamber 8.

It shall be understood that combustion 90 chamber structure of the character herein disclosed may be utilized to heat, in any suitable manner, one or more heat-absorption structures of types different from that disclosed in Fig. 1. For example, a single heat absorption 95 structure may receive heat by radiation from the wall structure of a metallic combustion chamber while at the same time the hot gases passing therefrom are utilized to heat the same absorption structure, for example, by 100 convection in part at least, or, two or more heat absorption structures may be similarly heated.

What we claim is:

1. Apparatus for heating petroleum comprising a combustion chamber having radiating wall structure of refractory metal, heat absorption structure disposed in a fixed and predetermined position with respect to said radiating structure and comprising a 110 bank of tubes traversed by the petroleum and receiving heat from said wall structure by radiation, and means for effecting combustion in said chamber at a rate to maintain said radiating metal at incandescence, said metal 115 being chemically inert at incandescence to the products of combustion.

2. The combination with a radiation combustion chamber comprising radiating structure of refractory metal, of means for burning fuel in said chamber at a rate to maintain the radiating metal incandescent, said metal at incandescence continuing chemically inert to the products of combustion and a bank of tubes through which fluid is passed 120 heated preponderantly by radiation from said refractory metal.

3. Heat transfer apparatus comprising a combustion chamber having a radiating wall structure of refractory metal, a bank of tubes 125

- through which fluid is passed disposed in fixed and predetermined position with respect to and heated substantially solely by radiation from said radiating structure, and means for burning fuel in said chamber at a rate to maintain said radiating metal at incandescence, said metal at incandescence being chemically inert to the products of combustion.
4. Heat transfer apparatus comprising a heating chamber, a radiation combustion chamber disposed in said heating chamber having a heat-radiating wall of refractory metal, a bank of tubes traversed by fluid to be heated disposed in said heating chamber in fixed and predetermined position with respect to said refractory metal wall from which said tubes are heated substantially solely by radiation, and means for effecting combustion of fuel in said combustion chamber at a rate to maintain said wall at incandescence, said wall at incandescence being chemically inert to the products of combustion.
5. Heat transfer apparatus comprising a heating chamber, a radiation combustion chamber disposed in said heating chamber having a heat-radiating wall of refractory metal, tubular heat absorption structure traversed by fluid to be heated disposed in said heating chamber in fixed and predetermined position with respect to said refractory metal wall from which said tubular structure is heated substantially solely by radiation, means for effecting combustion of fuel in said combustion chamber at a rate to maintain said wall at incandescence, said wall at incandescence being chemically inert to the products of combustion, and a second heat absorption structure through which said fluid is passed heated by convection by said products of combustion.
6. Petroleum heating apparatus comprising a heating chamber, a radiation combustion chamber having a heat-radiating wall of refractory metal, a bank of tubes disposed in said heating chamber in fixed and predetermined position with respect to said refractory wall and heated substantially solely by radiation from said wall, means for passing petroleum through said tubes, and means for effecting combustion of fuel in said combustion chamber at a rate to maintain said wall at incandescence, said wall at incandescence being chemically inert to the products of combustion.
7. Petroleum heating apparatus comprising a heating chamber, a radiation combustion chamber having a heat-radiating wall of refractory metal, tubular heat absorption structure disposed in said heating chamber in fixed and predetermined position with respect to said refractory wall and heated substantially solely by radiation from said wall, means for passing petroleum through said tu-
- bular structure, means for effecting combustion of fuel in said combustion chamber at a rate to maintain said wall at incandescence, said wall at incandescence being chemically inert to the products of combustion, and a second tubular heat absorption structure through which said petroleum is passed heated by convection by said products of combustion.
8. Apparatus for heating a fluid comprising a heating chamber, a radiation combustion chamber disposed in said heating chamber having a heat radiating wall of a metal, a bank of tubes conducting a fluid to be heated disposed in said heating chamber in good heat transfer relation with respect to said wall from which said tubes are heated substantially solely by radiation, means for effecting combustion of fuel in said combustion chamber at a rate to maintain said wall at incandescence, said wall having high heat conductivity, and the tubes being adapted to absorb heat at substantially the rate of radiation by the wall, to prevent melting or deterioration of the wall.
9. Apparatus for heating a fluid comprising a heating chamber, a radiation combustion chamber disposed in said heating chamber having a heat radiating wall of a metal, a bank of tubes for containing a fluid to be heated disposed in said heating chamber in good heat transfer relation with respect to said wall from which said tubes are heated substantially solely by radiation, means for effecting combustion of fuel in said combustion chamber at a rate to maintain said wall at incandescence, said wall having high heat conductivity, and the tubes being adapted to absorb heat at substantially the rate of radiation by the wall, to prevent melting or deterioration of the wall, said wall also being composed of a metal which is chemically inert to the products of combustion at the operating temperature.
10. Apparatus for heating a fluid comprising a heating chamber, a radiation combustion chamber disposed in said heating chamber having a heat radiating wall of a metal, a bank of tubes conducting a fluid to be heated disposed in said heating chamber in good heat transfer relation with respect to said wall from which said tubes are heated substantially solely by radiation, means for effecting combustion of fuel in said combustion chamber at a rate to maintain a temperature of the order of several thousand degrees Fahrenheit, the said wall being composed of a metal which has high heat conductivity, and the tubes being adapted to absorb heat at substantially the rate of radiation by the wall, to prevent melting or deterioration of the wall at the temperature maintained.
11. Apparatus for heating a fluid comprising a heating chamber, a radiation combustion chamber disposed in said heating chamber

ber having a heat radiating wall of a metal, a heat absorption structure for containing a fluid to be heated disposed in said heating chamber in good heat transfer relation with respect to said wall from which said absorption structure is heated substantially solely by radiation, means for effecting combustion of fuel in said combustion chamber at a rate to maintain a temperature of the order of 3200° Fahrenheit, the said wall being composed of a metal which has high heat conductivity, and the absorption structure being adapted to absorb heat at substantially the rate of radiation by the wall, to prevent melting or deterioration of the wall at the temperature maintained, the metal of said wall also being chemically inert to the products of combustion at the said operating temperature.
